CLAIM

The ornamental design for an applicator for suntan lotions and other liquids, as shown and described.

DESCRIPTION

FIG. 1 is a perspective view of an applicator for suntan lotions and other liquids showing my new design;

FIG. 2 is a top plan view thereof shown on a slightly larger scale;

FIG. 3 is a bottom plan view thereof;

FIG. 4 is a side elevational view taken from the right of FIG. 1;

FIG. 5 is a side elevational view taken from the left of FIG. 1;

FIG. 6 is a rear elevational view thereof; and

FIG. 7 is a front elevational view thereof.
